UNITED STATES PATENT OFFICE.

JOSEPH F. FRADLEY, OF BROOKLYN, NEW YORK.

DESIGN FOR A FINGER-BOWL.

SPECIFICATION forming part of Design No. 24,332, dated May 28, 1895.

Application filed February 1, 1895. Serial No. 537,032. Term of patent 3½ years.

To all whom it may concern:

Be it known that I, JOSEPH F. FRADLEY, of the city of Brooklyn, county of Kings, and State of New York, have invented and produced a new and original Design for Finger-Bowls, of which the following is a specification.

My design consists of a finger bowl having a handle extending from the upper portion and made of open work foliate construction.

10 In the accompanying drawings, Figure 1 is a top view of a finger-bowl embodying my design. Fig. 2 is a side view of the same.

Similar letters of reference represent corresponding parts in both figures.

15 A is the bowl, it being shown as having an upward flare. It is surmounted by a bead, B, and this is indented near the lower edge. Two handles, C, are shown as extending from

the upper portion, and each of these is of an open work foliate design.

20 The leading or characteristic feature of the design consists of a bead surmounting the upper portion of a finger bowl and handles of a foliate configuration extending from the latter.

25 What I claim as my design, and desire to secure by Letters Patent, is—

The design for a finger bowl, substantially as herein shown and described.

30 In testimony whereof I have signed my name to this specification in the presence of two subscribing witnesses.

JOSEPH F. FRADLEY.

Witnesses:

EDWIN H. BROWN,

W. LAIRD GOLDSBOROUGH.
